DIGITAL CLOCK HOUSING

John E. Studer, Jr., Raritan Township, N.J., assignor to
Delta Transnational, Inc., New York, N.Y.

Filed Dec. 26, 1972, Ser. No. 318,695

Term of patent 7 years

Int. Cl. D10—01

U.S. Cl. D10—1

Fig. 1.

Fig. 2.

Fig. 3.

FIG. 1 is a front perspective view of a digital clock housing showing my new design;

FIG. 2 is a front elevational view thereof, the rear surfaces being flat and unornamented;

FIG. 3 is a left side elevational view thereof, the right side being a mirror image thereof.

The novel digital clock design is formed by placing a digital clock housing movement in a housing and thence placing this housing on a supporting base to form the complete design. The novel design while being ornamental in character is also particularly suitable for its purpose in that a digital time indicator can be easily read.

I claim:

The ornamental design for a digital clock housing, as shown and described.
